(57) **CLAIM**

The ornamental design for a nozzle sleeve, as shown and described.

DESCRIPTION

FIG. 1 is a front perspective view of a nozzle sleeve according to the present invention.

FIG. 2 is a side elevation view of the nozzle sleeve illustrated in FIG. 1.

FIG. 3 is a front elevation view of the nozzle sleeve illustrated in FIG. 1.

FIG. 4 is a top plan view of the nozzle sleeve illustrated in FIG. 1.

FIG. 5 is a bottom plan view of the nozzle sleeve illustrated in FIG. 1; and,

FIG. 6 is a bottom perspective view of the nozzle sleeve illustrated in FIG. 1.

The broken lines in FIG. 1 illustrate an outline of an inner edge of a portion of the nozzle sleeve.
